WINDOW ASSEMBLY

William D. Bayley, Springfield, Ohio

Application October 25, 1937, Serial No. 170,873

24 Claims. (Cl. 189—64)

This invention relates to detention window assemblies and in more particular to windows wherein detention means are incorporated into the window assembly.

5 This application is a continuation-in-part of my copending application Serial No. 82,847 filed June 1, 1936, for Window assembly, wherein the claims relate to the interlocking arrangement of the bars, the key bars, etcetera, without reference to the capping members.

An object of this invention is to provide a window assembly that is cheap, efficient, dependable and sufficiently strong for normal usage.

15 Another object of this invention is to provide a closure assembly that may be hooked into position in registry with the ventilating area irrespective of which spaces have been left vacant for that purpose.

Another object of this invention is to provide 20 capping members of tool resistant material for some of the muntin bars, so as to protect the same from willful and unlawful severance by inmates.

Other objects and advantages reside in the 25 construction of parts, the combination thereof and the mode of operation, as will become more apparent from the following description.

Fig. 1 is a perspective view of my preferred embodiment.

30 Fig. 2 is a vertical sectional view taken substantially on the line 2—2 of Fig. 1.

Fig. 3 is a horizontal sectional view taken substantially on the line 3—3 of Fig. 1.

Fig. 4 is a sectional view taken substantially on 35 the line 4—4 of Fig. 1.

Fig. 5 is a sectional view of another modification taken on the line 5—5 of Figures 6 and 7.

Fig. 6 is a sectional view taken substantially on 40 the line 6—6 of Fig. 5.

Fig. 7 is another horizontal sectional view taken substantially on the line 7—7 of Fig. 5.

Fig. 8 is a sectional view taken substantially on 45 the line 8—8 of Figures 6 and 7.

Figure 9 is a cross sectional view taken substantially on the line 9—9 of Fig. 2.

In some types of duo-functional window assemblies where the transversely arranged bars function both as detention bars and as muntin bars, difficulties have been encountered in securing the necessary cheapness of construction without sacrificing the appearance and efficiency of the window. This is further complicated when providing adequate protection across the more vulnerable area, that is, across the ventilating area. This has been accomplished in part by

providing interlocking detention bars, which have been shown and described in my application Serial No. 82,847. This has been further accomplished by providing a closure unit for the ventilating area attachable in the field to the main structure and providing capping members of tool resistant material for the muntin bars. 5

In the present modification the vertical muntin bars 10 constitute eye bars having openings or eyes 12 longitudinally disposed with respect to the web of the vertical bars 10, as more fully disclosed and claimed in the above referred to copending application. These vertical bars 10 may be T-shaped in cross sectional area, or any other suitable shape. As the side bars 14 are embedded in the masonry, these bars need not necessarily be the same shape as the vertical bars 10; but may have oppositely disposed flanges 16 and 18, the former receiving the glazing 20 and the latter embedded in the masonry. The bars 14 may also be provided with eyes or openings similar to and aligned with the openings in the webs of the vertical bars 10. 15

The horizontal muntin bars 22 constitute the needle bars and may be T-shaped in cross sectional area, the stem of the T being provided with a downwardly projecting flange 24 at one side thereof, to give rigidity to the bar to provide protection to the key bars, thereby protecting the bar against erosion caused by rain, snow or moisture from the air. The needle bars 22 are passed 20 through the eyes 12 of the eye-bars 10 and locked in position, as more fully disclosed in my copending application Serial No. 82,847. 25

Rectangular duo-functional key and detention bars 32 are then passed through the enlarged portion of the eye 12, so as to hold the needle bar in position. The key bars 32 extend horizontally in close spaced relation and preferably on the under side of the muntin bars 22. The key bars 32 may be nestled in the corner formed by the web and the downwardly projecting flange 24. When the key bars 32 are associated with detention windows, these key bars may be made of tool resistant material and thus interfere with 40 the easy severance of the muntin bars extending in parallel relation thereto. By this structure the higher priced material is confined to the key bar, cheaper material being used in the eye bars, thereby effecting economy and cheapness. The 45 vertical muntin bars 10 are not protected against sawing or severance by the key bars 32.

For institutions used in confining or excluding "hard-boiled" criminals or others, additional protection may be necessary. Without additional 50 55

protection it is possible for the inmates to sever the vertical muntin bars 10, the severed ends giving the inmates a good leverage to twist, bend or deflect the horizontal detention bars even though these are not severed.

If tool resistant bars were extended in parallel relation to the vertical muntin bars and positioned in a manner similar to the horizontal key bars 32, such bars would interfere with the glazing of the glazed spaces of the window. In the modification disclosed in Fig. 4, bars 40 of tool resistant material extend in parallel relation and in close contact with the muntin bars 10 extending across the ventilating area, the tool resistant bars 40 terminating at the boundary of the ventilating area. The detention bars 40 prevent the easy cutting of the portions of the muntin bars 10 functioning as detention bars, extending across the ventilating area, which is the more vulnerable portion of the window.

The detention bars 40 protect the more vulnerable portion of the window. However, these do not take care of the portions of the muntin bars extending across the glazed areas of the window. The portions of the muntin bars 10 extending across the glazed area are protected by capping members 50 overlying the flanges of the muntin bars 10. Bars of other shapes can be used equally as well in many types of structures. These capping members 50 prevent the severance of the muntin bars 10; but do not interfere with the glazing of the fixed spaces, as the capping members 50 are placed on the inside of the glazing along the flanges. The capping members 50, which are preferably made from tool resistant material, are very effective in preventing the inmates from severing the muntin bars above or below or to either side of the ventilating area. The capping members 50 could extend uninterruptedly from the top to the bottom of the window across the ventilating area, providing the closure frame is provided with clearance for these capping members 50. This, however, will result in a thicker or more massive structure, as the closure for the ventilating area would probably project further outwardly away from the main structure than the closure in a window where the capping members do not extend across the ventilating area. If the capping members 50 were extended across the ventilating area the muntin bars 40 of tool resistant material could be eliminated for some types of structures. The sum of the thicknesses of the portions of the flanges extending in a direction normal to the glazing is considerably greater than the portion of the capping member 50 extending parallel to the glazing and overlying the flanges. Thus, the portion of the capping members extending in a direction normal to the glazing is much stronger than the portion forming the bottom of the channel.

Each of the capping members 50 located above the ventilating area may be provided with downwardly extending portions 51, terminating in a hook or lip portion 53, arranged in spaced relation from the downwardly projecting flange of the horizontal muntin bar 22 forming the boundary along the top of the ventilating area.

A fixed frame 60 supports a movably mounted closure overlying the ventilating area. The frame 60 terminates in an upwardly projecting flange 55 that is seated underneath the lip 53. The flange 55 is preferably provided with a longitudinal recess 57, supporting suitable sealing material closing the juncture between the top of the closure frame 60 and the horizontal muntin bar

extending across the top of the ventilating area. Suitable holes 52 extending through the flanges of the muntin bars 10 permit the pouring of fused metal to weld member 50 to the muntin bars. These holes 52 may be positioned between the intersection of the transversely disposed muntin bars, so that the same weld unites three parts together without leaving exposed holes and without leaving exposed welds, that is, the vertical and the horizontal bars together with the capping member 51 are united by a single weld extending between the flanges of the vertical and the horizontal bars and terminating in union with the capping member 51. The putty holding the glazing conceals the weld and protects it from the elements.

A clearance 59 is provided above the flange 55, so as to permit the insertion of the closure frame 60 by projecting the flange 55 into the clearance 59, moving the lower portion of the closure frame 20 towards the main frame over the sill 64 to permit the closure to drop into position. The clearance 59 may first be filled with a suitable plastic to provide weather tightness and rigidity of the closure frame. The crevice between the downwardly projecting flange of the closure 60 and the sill 64 may be filled with suitable plastic or yieldable material 61.

In the present instance the closure includes a movable member not shown, movably attached to the frame 60. A sill 64, interlocking the upwardly projecting flange of the muntin bar extending across the bottom of the ventilating area, supports the bottom of the frame 60. The closure that is movably mounted may be pivoted at the bottom, at the top, at either side, in the center or otherwise mounted in position.

Referring to the modifications disclosed in Figs. 5 to 8 inclusive, the horizontal T-bars 70 have been provided with suitable openings for the reception of the vertical muntin bars 76. The flanges 80 are arranged in flush relation with respect to the flanges 82, as has been more fully described in my copending application Serial No. 82,847. The needle bars 76, after being properly positioned as described in my copending application, are locked in position by key bars 84, preferably made of tool resistant material and square or rectangular in cross sectional area. The key bars 84 are preferably aligned and symmetrically disposed with respect to the webs and the flanges of the muntin bars 76, so that the muntin bars 76 and the key bars 84 cooperate to form a pair of channels, one on either side of the webs of the muntin bars 76. In some structures the dividing web 76 may be offset, so as to provide a shallow channel on one side and a deeper channel on the other side to facilitate glazing. By arranging the flanges and the key bar 84 in symmetrical relation, the offset relation of the web is inconspicuous after the window is completed.

For this type of construction it is desirable that the maximum width of the T-bars 76 be somewhat less than the width of the web of the horizontal bars 70. The key bars 84 are positioned along the outer edge of the webs of the T-bars 76, so as to have sufficient clearance for the insertion of the glazing. That being the case, the duo-functional detention and T-bars 84 may extend uninterruptedly across the ventilating area and the glazed spaces.

In this modification it is not absolutely necessary in order to provide proper protection across the ventilating area to have the muntin bars extend continuously across both the ventilating

area and the fixed glazed spaces. The muntin bars may terminate at the ventilating area, thereby saving material and improving the visibility of this portion of the window. Suitable detention means extending across the ventilating area may be used to provide adequate protection across the more vulnerable area of the window.

In the modification disclosed in Figs. 5 and 7, transverse detention bars 86, which may have notches in the sides thereof, extend across the ventilating area and are welded to the vertical T-bars 84. The ends of the detention bars 86 are preferably welded to the muntin bars bounding the sides of the ventilating area.

In some structures the horizontal bars 86, or for that matter the vertical bars 84, may be eliminated at the fixed glazed spaces. If so, either the horizontal bars or the vertical bars, or both, may be provided with capping members 50 shown in Fig. 6, which capping members are similar to those which have already been described in connection with the modification disclosed in Figs. 1 to 4 inclusive, and shown in detail in Fig. 3.

In Fig. 8 the capping members along the sides of the window extend in overlapping relation with respect to the flanges 18 of the muntin bars 14 bounding the sides of the window, so as to have portions of the capping members embedded in the masonry of the wall. In some types of structures it is not necessary to have the capping members embedded in the masonry. The capping members could then terminate in a manner similar to that shown in Fig. 7.

The unglazed ventilating area is preferably provided with a closure, only the frame 90 of which has been shown, as any suitable movable closure may be mounted upon the frame 90 to close the ventilating area.

The muntin bar extending across the top of the ventilating area is provided with a metallic capping member 94 welded to the upwardly projecting flange through suitable fusing holes or pockets 96. These fusing holes or pockets 96 are preferably located between the juncture of the angles of the vertical and the horizontal muntin bars, so that the weld holds three parts together, that is, the vertical and horizontal muntin bars and the capping member 94. Capping members 50 and the key bars 84 may also be held in position by suitable welds passed through fusing holes. Again, three parts may be held together by a single weld. The capping member 94 is provided with a downwardly projecting flange overlying an upwardly projecting flange 92 of the closure frame 90.

The lower portion of the closure frame 90 is supported upon the sill 64 in a manner similar to that already described in connection with the preferred embodiment. Sufficient clearance has been provided so that the closure assembly may be placed in position by inserting the upwardly projecting flange 92 under the downwardly projecting flange or the lip portion of member 94 and then the lower portion of the frame 90 moved toward the main frame and slipped over the top of the sill 64 as it is dropped into position. Thus, it is seen that the closure for the ventilating area may be placed in position after the window has been erected in the building, thereby reducing the cost of production, as it is possible to have the closure glazed and completely assembled on the job or at the factory before the closure and its frame is mounted in position.

The channel 57 in the closure 90 supports

putty or suitable sealing material for sealing the closure along three sides thereof. The crevice formed between the downwardly projecting flange 92 and the sill 64 is preferably filled with suitable plastic or yieldable material 61, so as to provide weather tightness.

As member 50 and member 94, as well as the sill 64, are preferably made of tool resistant material, these members cooperate to prevent the severance of the muntin bars.

Although the preferred modification of the device has been described, it will be understood that within the purview of this invention various changes may be made in the form, details, proportion and arrangement of parts which generally stated, consist in a device capable of carrying out the objects set forth, in the novel parts, combination of parts and mode of operation, as disclosed and defined in the appended claims.

Having thus described my invention, I claim:

1. A detention window assembly including a plurality of transversely arranged muntin bars dividing the window into a plurality of spaces, some of said spaces being glazed leaving at least one space larger than one of said glazed spaces vacant for a ventilating area, the muntin bars aligned with the ventilating area terminating at the boundary thereof, some of said muntin bars constituting needle bars extending through eyes of the remaining bars, duo-functional key and detention bars arranged in parallel relation with respect to the needle bars and extending through the eyes of the remaining bars to interlock the bars in a fixed relation with respect to each other, said duo-functional bars extending across the ventilating area, additional detention means extending across the ventilating area cooperating with the duo-functional bars to prevent the escape of a human being therethrough, and tool resistant means associated with the eye bars to prevent the severance thereof.

2. In a detention window assembly a plurality of transversely arranged T-shaped muntin bars dividing the window into a plurality of spaces, at least some of which are glazed, and capping members of tool resisting material overlying the flanges of some of the muntin bars to deter severance thereof, said capping members having flanges extending inwardly in substantially parallel relation with respect to the stems of the T-bars.

3. In a detention window assembly a plurality of transversely arranged T-shaped muntin bars dividing the window into a plurality of spaces, some of which are glazed leaving a group of spaces vacant for ventilating area across which the muntin bars extend, means associated with the muntin bars extending across the ventilating area for preventing the escape of human bodies through the ventilating area, and capping members associated with the portions of the muntin bars extending across the fixed glazed areas to deter the severance thereof.

4. In a detention window assembly a plurality of transversely arranged T-shaped muntin bars dividing the window into a plurality of spaces, some of which are glazed leaving a group of spaces vacant for ventilating area across which the muntin bars extend, means associated with the muntin bars extending across the ventilating area for preventing the escape of human bodies through the same, tool resistant bars arranged in parallel relation to some of the portions of the muntin bars extending across the ventilating area, and capping members overlying the flanges

of the portion of the T-bars extending across the fixed glazed spaces for deterring the severance thereof.

5. In a detention window assembly a plurality of transversely arranged T-shaped muntin bars dividing the window into a plurality of spaces, some of which are glazed leaving a group of spaces vacant for ventilating area across which the muntin bars extend, detention means extending across the ventilating area for preventing the escape of human bodies therethrough, and tool resistant capping members overlying the flanges of the portions of some of the muntin bars extending across the fixed glazed areas, said capping members including extensions overlying portions of the muntin bars bounding the ventilating area.

6. In a detention window assembly a plurality of transversely arranged T-shaped muntin bars dividing the window into a plurality of spaces, some of which are glazed leaving a group of spaces vacant for ventilating area across which the muntin bars extend, detention means extending across the ventilating area for preventing the escape of human bodies therethrough, a closure for the ventilating area including a frame having outwardly projecting flanges juxtaposed with respect to some of the flanges of the muntin bars bounding the ventilating area, and capping members of tool resistant material overlying the flanges of the portions of some of the muntin bars extending over the fixed glazed spaces, said capping members including lips overlying the flanges of the frame so as to hold the frame in position.

7. In a detention window assembly a plurality of transversely arranged T-shaped muntin bars dividing the window into a plurality of spaces, some of which are glazed leaving a group of spaces vacant for ventilating area across which the muntin bars extend, detention means extending across the ventilating area for preventing the escape of human bodies therethrough, a closure for the ventilating area, said closure including a frame having outwardly projecting flanges juxtaposed with respect to some of the flanges of the muntin bars bounding the ventilating area, detention means extending across the ventilating area for preventing the escape of human bodies therethrough, and capping members overlying the flanges of the portions of some of the muntin bars extending across the fixed glazed area, said capping members including lips overlying the flanges of the frame of the closure so as to hold the same in position.

8. In a detention window assembly a plurality of transversely arranged T-shaped muntin bars dividing the window into a plurality of spaces, some of which are glazed leaving a group of spaces vacant for ventilating area across which the muntin bars extend, detention means extending across the ventilating area for preventing the escape of human bodies therethrough, a closure for the ventilating area including a frame having outwardly projecting flanges overlapping some of the flanges of the muntin bars bounding the ventilating area, means associated with the portion of some of the muntin bars extending across the fixed glazed spaces for preventing the severance thereof, said means including a lip overlapping the flanges of the frame of the closure to hold the same in position, and a tool resistant member fixedly attached to one of the flanges of the muntin bar bounding the ventilating area, said member having a portion there-

of overlapping the flange of the closure frame, said member deterring the severance of the muntin bar bounding the ventilating area and cooperating with the lips to hold the closure frame in position.

9. In a detention window assembly, a plurality of flanged muntin bars dividing the window into a plurality of spaces, said muntin bars having portions thereof projecting beyond the glazing, and capping members of tool resisting material, said capping members having channels into which portions of the muntin bars extend to deter the severance thereof, the inner walls of the channel being arranged substantially parallel to the flanges of the bars.

10. In a detention window assembly, a plurality of muntin bars dividing the window into a plurality of spaces, some of which are glazed leaving a group of spaces vacant for ventilating area across which the muntin bars extend, portions of the muntin bars extending beyond the glazing of the glazed spaces, and capping members associated with the portions of the muntin bars extending across the fixed areas to deter the severance thereof, said capping members bounding at least two sides of the portions of the muntin bars extending beyond the glazing and terminating at the ventilating area.

11. In a detention window assembly, a plurality of muntin bars dividing the window into a plurality of spaces at least some of which are glazed, said muntin bars having portions thereof extending beyond the glazing of the glazed spaces, and capping members of tool resisting material overlying said portions to deter the severance thereof, said capping members having flanges extending inwardly in substantially parallel relation with respect to the sides of the muntin bars.

12. In a window assembly having a plurality of transversely disposed muntin bars dividing the window into a plurality of spaces, some of which are glazed leaving at least one space vacant as a ventilating area, a downwardly projecting lip portion arranged in spaced relation from the outer surface of the muntin bar extending along the top of the ventilating area, a closure assembly for the ventilating area, said closure assembly including a movable closure mounted in a fixed frame portion having an upwardly projecting flange extending under said lip portion, and means cooperating with the lip portion to hold the frame in fixed relation with respect to the ventilating area.

13. In a window assembly having a plurality of transversely disposed muntin bars dividing the window into a plurality of spaces some of which are glazed leaving at least one space vacant as a ventilating area, a downwardly projecting lip portion arranged in spaced relation from the outer surface of the muntin bar extending along the top of the ventilating area, a closure assembly for the ventilating area, said closure assembly including a movable closure for closing the ventilating area, said movable closure being mounted in a fixed frame portion having an upwardly projecting flange extending under said lip portion to hold said frame along the top, and means for holding the bottom of the frame in fixed relation with respect to the bottom of the ventilating area.

14. In a window assembly having a plurality of transversely disposed muntin bars dividing the window into a plurality of spaces some of which are glazed leaving at least one space vacant as a ventilating area, a downwardly projecting lip portion arranged in spaced relation from the

outer surface of the muntin bar bounding the top of the ventilating area, an upwardly projecting lip portion arranged in spaced relation from and supported upon the muntin bar extending along the bottom of the ventilating area, and a closure assembly for the ventilating area, said closure assembly including a movable closure mounted in a fixed frame portion having an upwardly projecting flange underlying the downwardly projecting lip portion across the top of the ventilating area, and a downwardly projecting flange interlocking the lip portion extending along the bottom of the ventilating area, so as to hold the frame portion in fixed spaced relation with respect to the muntin bars.

15. In a window assembly having a plurality of transversely disposed muntin bars dividing the window into a plurality of spaces some of which are glazed leaving at least one space vacant as a ventilating area, means cooperating with the muntin bars extending along the top of the ventilating area to form a channel, a member having an upwardly projecting lip portion extending along the bottom of the ventilating area, said member overlapping a portion of the muntin bar extending across the bottom of the ventilating area, and a closure assembly for the ventilating area, said closure assembly including a movable closure mounted in a fixed frame having an upwardly projecting flange seated in the channel along the top of the ventilating area, and a downwardly projecting flange overlying the lip portion extending along the fixed frame in fixed spaced relation with respect to the muntin bars.

35. 16. In a window assembly having a plurality of transversely disposed muntin bars dividing the window into a plurality of spaces some of which are glazed leaving at least one space vacant as a ventilating area, overlapping lip portions located on at least two oppositely disposed sides of the ventilating area arranged in spaced relation with the muntin bars extending along said sides, and a closure assembly having means interlocking said lip portions so as to support the closure assembly upon the muntin bars of the window assembly.

17. A metallic window assembly including a plurality of transversely disposed muntin bars, one set of muntin bars having flanges projecting in parallel relation with respect to the glazing, a capping member having a lip portion arranged in parallel relation with respect to the flanges of one of the muntin bars and supported in spaced relation therefrom, said lip portion cooperating with the flange to form a channel, and a closure for the space subtended by the channel, said closure having an edge projecting into the channel and held in position by the capping member.

18. A metallic window assembly having a plurality of transversely disposed toolable muntin bars dividing the window into a plurality of spaces some of which are glazed leaving a group of spaces vacant for a ventilating area, the muntin bars extending along the boundary of the ventilating area having flanges projecting into the ventilating area in parallel relation with respect to the glazing, a capping member of tool resisting material overlying at least one of the muntin bars and contiguous thereto, said capping member having a flange arranged in parallel relation with respect to one of the inwardly projecting flanges bounding the ventilating area, said flanges cooperating to form a channel, and a closure for the ventilating area having a flange projecting into the channel so as to be held in position thereby.

19. A metallic window assembly including a plurality of transversely disposed muntin bars dividing the window into a plurality of spaces, means for closing the spaces, said means including glazing, some of said muntin bars having flanges projecting in planes parallel to the glazing, and a capping member of tool resistant material for at least one of the muntin bars, said capping member having a flange projecting in parallel relation but offset from the flange of the muntin bar, said flanges cooperating to form a channel into which the means for closing the adjacent space projects.

20. A metallic window assembly having a metallic frame, including a plurality of transversely disposed metallic muntin bars dividing the window into a plurality of spaces some of which are glazed leaving a group of spaces unglazed as a ventilating area, the portion of the frame extending across the top of the ventilating area having a downwardly projecting channel, the portion of the frame extending across the bottom of the ventilating area including a sill portion having an upwardly projecting flange, and a closure assembly for the ventilating area including a closure frame having a flange projecting up into the channel extending across the top of the ventilating area, said closure frame also having a flange along the bottom thereof overlapping the upwardly projecting flange along the sill portion.

21. A detention window assembly including a plurality of transversely arranged muntin bars dividing the window into a plurality of spaces, some of said bars constituting flanged needle bars passing through eyes in the remaining bars, duo-functional key and detention bars passing through said eyes in parallel relation to the needle bars and arranged to interlock the bars in fixed relation, and additional bars overlapping at least portions of the eye bars to prevent severance thereof.

22. In a window assembly a composite muntin bar structure including a pair of members one of which is a glass supporting member, one of said members being of tool resistant material, the other of toolable material, one of said members constituting portions directed in two directions, one portion in parallel to the glazing, the remainder of said member in a direction substantially normal to the glazing, said remainder being thicker than the portion extending parallel to the glazing, said parts being united by a weld extending through a fusing recess in one of said members and engaging the other member to hold the members in rigid relation to each other.

23. In a window assembly, three transversely disposed bars some of which function as muntin bars, at least one of said bars having a fusing hole for receiving fusing material uniting the three bars into a unitary structure.

24. A window assembly having glazing held in position by putty, said assembly including at least three transversely disposed bars, at least two of said bars constituting intersecting bars, an aperture extending through the juncture of the two bars and terminating in a surface of the third bar, fusing material in said juncture uniting the three bars by a unitary weld, the surface of the weld being concealed by the putty holding the glazing in position.
